UNITED STATES PATENT OFFICE.

ALLEN C. BRANTINGHAM, OF TOLEDO, OHIO, ASSIGNOR TO NORDYKE & MARMON COMPANY, OF INDIANAPOLIS, INDIANA, A CORPORATION OF INDIANA.

MILL.

1,282,181.

Specification of Letters Patent.

Patented Oct. 22, 1918.

Application filed October 23, 1916. Serial No. 127,070.

To all whom it may concern:

Be it known that I, ALLEN C. BRANTINGHAM, a citizen of the United States of America, residing at Toledo, Lucas county, Ohio, have invented new and useful Mills, of which the following is a specification.

This invention relates to mechanism for subdividing or disintegrating material.

This invention has utility, especially in the further breaking up of fractured particles and flakes, as of cereal, for instance in flour mill work, between the mills and sifters.

Referring to the drawings:

Figure 1 is a longitudinal medial section through an embodiment of the device as a scroll grinder or mill; and

Fig. 2 is an elevation of the discharge end of the device, parts being broken away.

The base 1 carries the long bearing 2 for the shaft 3, which has at one outboard end 4 the driving pulley 5. This shaft 3, at its inner overhung end, carries the enlarged hub 6, upon which is mounted the pair of scrolls 7, forming the double pitch rotary scroll impeller means disposed in the housing 8 carried by the base 1. This housing 8 has the supply chute 9 providing an intake opening for material to be treated. At its opposite end the housing carries the stepped cone section 10 which has, on the flattened radially extending portions thereof, an outer series of four pins 11, and an inner series of four longer pins 12, the longer pins being on the stepped portion a shorter distance from the axis of shaft 3. Pin 11 and pin 12 are radially alined as to their axes in their axial extent, and such pairs of pins 11 and 12 are disposed at 90° distances about the housing 8.

Opposing these axially extending pins or projections 11 and 12 are three relatively rotatable sets of pins carried by the scroll means and its hub. The outer and shortest pins 13, and the next set of pins 14 are disposed to have project therebetween the pin 11, and are carried by one of the scrolls 7.

Radially inward from these pins 13, 14, carried by the scroll 7 is a still longer pin 15 carried by the hub 6 and extending axi-

ally in the space within the region of the pins 12. Each of the two scrolls 7 has one set of pins 13, 14, with the pin 15 on the hub inwardly therefrom, so there are two of each of these pins 13, 14, 15, diametrically arranged.

Opposing this stepped cone 10 is the reverse cone 16 mounted on the hub 17, having axially radially extending wings 18 for pins 19 on the hub 6, whereby, in the rotation of the hub 6, the cone member 16 is rotated with this hub 6 and relatively to the cone member 10. This cone member 16, with its hub 17, is loosely mounted on the stem 20 coaxial with the shaft 3. The stem is rigidly supported against lateral vibration by the bearing 21, but is free to rotate therein. This bearing 21 is carried by the extension 22 of the housing which provides the discharge way 24 from the grinder or mill, the controlled discharge outlet being between the outer flare portion of the cone 16, and the inward flare of the reverse cone shaped member 10. This adjustable clearance annular discharge opening between the pair of cone members is controlled by a yielding adjustment. The hand wheel 25 may be rotated to compress the spring 26, and thus adjust the yielding resistance as may be desired in the character of material and feed rate thereof from the mill, by causing the collar 27 on the shaft 20 to coact with the hub 17.

The thrust from the discharge cone may be taken up from the scrolls by the anti-friction ring bearing 28 coacting with the lubricating collar 29 on the shaft 3. The rate of rotation of the scroll means may be varied from 400 to 1,000 R. P. M. in accordance with the material being handled, and this material is impelled into the stepped cone member 10, wherein the pins laterally swish the material backward and forward, the steps in the member 10 precluding any direct sliding of surface contact material to the discharge. There is accordingly effective disintegration at the projections or pins and a uniform discharge between the relatively rotatable reverse cones 10, 16. Fur-

ther, this adjusted control of the cone 16 is a unit in itself apart from the scroll impellers and the shaft mounting.

The device is accordingly one of simple structure and which may be readily installed for effective operation of great capacity with a minimum of upkeep.

What is claimed and it is desired to secure by United States Letters Patent is:

10 1. A scroll disintegrator embodying a housing, scroll means therein, axially extending projecting means carried by the scroll means, and opposing projecting means carried by the housing, said projecting means being in series of different lengths.

20 2. A scroll disintegrator embodying a housing, scroll impeller means in the housing and providing radial series of axially extending pins, said housing being stepped, and opposing axially extending pins mounted on the steps of the housing in a plurality of radial series staggered to interfit with the pins of the scroll means.

25 3. A disintegrator embodying rotary impeller means, a pair of oppositely tapering members providing a discharge opening axially of the impeller means, and an agitator device between the means and opening for interrupting material travel from the means 30 to the opening, said device including interfitting concentric series of pins.

35 4. A disintegrator embodying impeller means, a pair of conical members providing adjacent the larger diameter of one member and the smaller diameter of the other member an annular discharge opening from the means, and radially spaced projections parallel to the axis of one of the conical members, said projections extending transversely 40 of a common radial plane for intercepting material travel from the means to the opening.

45 5. A disintegrator embodying impeller means, a pair of reversely conical members providing adjacent the larger diameter of one member and the smaller diameter of the other member, an annular discharge opening from the means, and axially overlapping relatively movable series of projections for 50 agitating the material in its travel from the means to the opening.

55 6. A disintegrator embodying impeller means, and a housing providing a chamber for the impeller means, said impeller means being rotatable and provided with an annular series of pins, said housing providing a conical portion for said chamber, said conical portion having material flow intercepting steps extending axially of the impeller 60 means, and pins on said steps interfitting with the impeller pins to interrupt radial inward material travel.

7. A disintegrator embodying a housing forming a chamber having an annular dis-

charge opening, impeller means in said chamber for directing material flow toward the discharge opening, said housing being provided with a conical portion extending away from the discharge opening and comprising successive material flow intercepting 70 continuous annular steps, pins on said steps, and opposing interfitting pins mounted for rotation as to the housing carried pins.

8. A disintegrator embodying impeller means, a conical first member having perpendicular to the cone axis material flow intercepting steps effective to interrupt material travel thereover, a relatively rotatable oppositely conical second member coacting with the conical first member to provide adjacent the smaller diameter of the first member and the larger diameter of the second member, an annular discharge opening from the impeller means, and means for yieldably adjusting the clearance between the members.

90 9. A rotary impeller mill embodying an overhanging shaft, rotary impeller means thereon, a housing for the impeller means, said housing beyond the impeller means being provided with a series of concentric steps terminating adjacent its minimum diameter in an annular opening, having its maximum diameter adjacent the minimum diameter region of the stepped portion of the housing 95 and a member in said opening tapering toward the shaft and oppositely from the steps of the housing, and means for adjusting the member independently of the impeller means for controlling discharge from 100 the housing.

105 10. A scroll disintegrator embodying an overhanging shaft, rotary scroll impeller means thereon, a housing therefor having a conical portion inwardly stepped to terminate adjacent its minimum diameter in a coaxial discharge way, and movable means having sliding connection with the shaft, centered by the shaft and operable for adjusting the clearance of the discharge way 110 independently of moving the scroll means, said movable means being tapered toward the shaft and the impeller means and having its maximum diameter adjacent the minimum diameter of the housing conical portion.

110 11. A disintegrator embodying an overhanging shaft, rotary impeller means thereon, and oppositely tapered members, one of which is connected to rotate with the shaft, 120 and to be adjusted independently of the impeller means, said members providing adjacent the larger diameter of one member and the smaller diameter of the other member an annular discharge opening concentric with the impeller means and intermediate the radial extent of the housing.

12. A disintegrator embodying a housing

provided with an annular outlet, a scroll for impelling material toward said outlet, means for mounting the scroll holding the scroll against other than rotary movement in the 5 housing, said housing tapering inward by steps from the fixed position of the scroll toward the outlet, pins projecting from the housing steps toward the scroll, pins mounted

on the scroll and projecting between the housing carried pins, and a gate connected 10 to rotate with the scroll but movable axially of the scroll for varying the effective opening of the outlet.

In witness whereof I affix my signature.

ALLEN C. BRANTINGHAM.
